DISPENSING CONTAINER

Robert Henderson, Philadelphia, Pa.

Application June 16, 1936, Serial No. 85,572

10 Claims. (Cl. 221—144)

This invention relates to dispensing containers, and has for an important object thereof the provision of a container capable of dispensing bulk materials of widely varying characteristics. Many materials of the same general type and utilized in the same fashion vary in different species to such an extent as to require dispensing containers having different sized openings as, for example, soap powder and soap flakes, and it is the purpose of this invention to provide in a single container a structure such that either of these materials, or materials having the same general characteristics, can be dispensed with equal facility.

A more specific object of the invention is the provision of a hopper-type container having controlling gate mechanism of the pivotal type which is so constructed that a variable sized dispensing opening may be provided.

A further object of the invention is the production of a structure of this character which may be readily and cheaply produced and will be durable and efficient in service.

These and other objects I attain by the construction shown in the accompanying drawings, wherein,

Fig. 1 is a perspective view of a dispensing container constructed in accordance with my invention;

Fig. 2 is a vertical sectional view therethrough showing the gate operated to provide a relatively small opening such as would be employed when using powdered soap;

Fig. 3 is a fragmentary sectional view showing the gate operated to provide a large opening;

Fig. 4 is a section on line 4—4 of Fig. 2;

Fig. 5 is a section on line 5—5 of Fig. 2;

Fig. 6 is a section on line 6—6 of Fig. 3; and

Fig. 7 is a section on line 7—7 of Fig. 3.

Referring now more particularly to the drawings, the numeral 10 generally designates a casing having arranged therein a hopper 11, and having at its lower end a suitable discharge mouth 12 spaced from the hopper. Extending across the casing adjacent one side of the hopper mouth is a shaft 13 at present shown as having one end thereof mounted in a bracket 14, and the opposite end thereof extended through the opposite wall of the casing and provided with

a handle 15. Secured to the shaft is a gate 16 which is of a size such that it will close only a portion of the hopper mouth. A spring 17 constantly tends to rotate the shaft in a direction maintaining this gate in its closed position, this spring being at present shown as coiled about

the shaft 13 with one end thereof engaged with bracket 14 and the opposite end thereof secured to gate 16. As a convenient method of providing the upper surface of this gate with an agitator, the extremity 17a of the spring is bent at 5 right angles and extended through the gate.

A second gate 18 is rotatably mounted upon the shaft and is provided with a sleeve-like extension 19 having at its end a projecting lug 20. Abutting the end of this sleeve and surrounding shaft 13 is a wedge piece 21 which abuts a wedge cam 22 slidable against the adjacent side wall of the casing and slotted for the passage of shaft 13 as at 23. This wedge cam has an angular extension 24 projecting through a bayonet 15 slot 25 formed in the casing wall above the handle lever 15. When this wedge cam is in its elevated position a flange 26 formed thereon is disposed in the path of lug 20 and prevents the sleeve, and accordingly the gate 18, from rotating. 20 When, however, this cam is in its lowered position, this lug clears the flange and the gate 18 may rotate.

The sleeve, and accordingly the wedge piece 21, are constantly urged toward this wedge cam 25 by a spring 27 surrounding the shaft 13 between the gates, and it will be obvious that movement of the wedge cam 22 from raised to lowered position, or vice versa, will cause longitudinal movement of the sleeve and gate 18. Gate 18 at all 30 times slightly overlaps gate 16, and when it is shifted to the left by depression of cam 22, the marginal edge thereof engages beneath the latch piece 28 secured to gate 16. It will be obvious that with the cam piece in the elevated position, 35 rotation of shaft 13 will merely cause operation of gate 16, gate 18 being held in its elevated position by engagement of the lug 20 with flange 26. When the cam piece is depressed, the two gates are locked to one another and rotation of shaft 40 13 will cause both gates to be opened. Gate 18 is preferably provided with an agitator member 29, as illustrated.

Since the construction above described is capable of considerable modification without in any 45 manner departing from the spirit of my invention, I do not wish to be understood as limiting myself thereto except as hereinafter claimed.

I claim:

1. In combination with a hopper, a pair of 50 pivoted gates each partially controlling the mouth of the hopper, means to independently open one of said gates, and means to connect the gates for simultaneous opening.

2. In combination with a hopper, a pair of 55

gates controlling the mouth of the hopper and pivotal about a common axis, means to independently move one of the gates from closed to open position, one of said gates being shiftable 5 in the general direction of its axis to either of two selected positions, means connecting the gates for simultaneous movement when said shiftable gate is in one of said positions and means holding the second gate against rotation 10 about its pivot when the movable gate is in the other of said positions.

3. In combination with a hopper, a gate to partially close the hopper mouth, a rotatable shaft to which said gate is secured, means normally maintaining said shaft in a position where the gate partially closes the hopper mouth, a second gate 15 for completing the closure of the hopper mouth and rotatably mounted on said shaft, means to hold said gate against rotation and in a position to close the hopper mouth, and means to release the holding means and to connect said second gate to the first-named gate 20 for rotation therewith.

4. In combination with a hopper, a pair of 25 pivoted gates each partially controlling the mouth of the hopper, means to independently open one of said gates, means to hold the other gate closed during independent opening of the first-named gate, and means to connect the gates 30 for simultaneous opening and to release said holding means.

5. In combination with a hopper, a pair of gates controlling the mouth of the hopper and pivotal about a common axis, means to independently move one of the gates from closed to open position, the other of said gates being shiftable 35 in the general direction of its axis to either of two selected positions, means connecting the gates for simultaneous movement when said 40 shiftable gate is in one of said positions, and means holding the shiftable gate against rotation about its pivot when said shiftable gate is in the other of said positions.

6. In combination with a hopper, a pair of 45 gates controlling the mouth of the hopper and pivotal about a common axis, means to independently move one of the gates from closed to open position, the other of said gates being shiftable 50 in the general direction of its axis to either of two selected positions, means connecting the gates for simultaneous movement when said

shiftable gate is in one of said positions, and means holding the shiftable gate against rotation about its pivot when said shiftable gate is in the other of said positions, adjacent edges of said gates being in permanently overlapped 5 relation and one of said gates including a catch to engage over the edge of the other thereof when the shiftable gate is moved to the first-named position.

7. In combination with a hopper, a gate to partially close the hopper mouth, a rotatable shaft to which said gate is secured, means normally maintaining said shaft in a position where the gate partially closes the hopper mouth, a second gate 10 for completing the closure of the hopper mouth and rotatably and longitudinally shiftable on said shaft, a latch operatively connecting said shiftable gate to the shaft when in one longitudinally adjusted position on the shaft and means to hold said gate against rotation and in a 15 position to close the hopper mouth when in the second position on said shaft.

8. In combination with a hopper, a gate to partially close the hopper mouth, a rotatable shaft to which said gate is secured, means normally maintaining said shaft in a position where the gate partially closes the hopper mouth, a second gate for completing the closure of the hopper mouth and rotatably and longitudinally shiftable 20 on said shaft, a latch operatively connecting said shiftable gate to the shaft when in one longitudinally adjusted position on the shaft, means to hold said gate against rotation and in a position 25 to close the hopper mouth when in the second position on said shaft, a spring urging said shiftable gate to the last-named position and a cam to move said shiftable gate to the first-named 30 position against the action of said spring.

9. In combination with a hopper, a pair of gates each partially controlling the mouth of the 35 hopper, means to independently open one of said gates, and means to connect the gates for simultaneous opening.

10. In combination with a hopper, a pair of gates each partially controlling the mouth of the 40 hopper, means to independently open one of said gates, means to hold the other gate closed during independent opening of the first-named gate, and means to connect the gates for simultaneous 45 opening and to release said holding means.

ROBERT HENDERSON.
